JEWELRY DISPLAY CASE

Earl Zimbler, New York, N.Y., assignor to Jewelcor Incorporated, New York, N.Y.

Filed Sept. 4, 1975, Ser. No. 610,497

Term of patent 14 years

Int. Cl. D6—04; D20—02
U.S. Cl. D6—173

FIG. 1

FIG. 1 is a front, top and right side perspective view of a jewelry display case showing my new design;

FIG. 2 is a rear, bottom and left side perspective view thereof; and

FIG. 3 is a front, top and right side perspective view thereof with the top removed and the transparent sides in an open position.

I claim:

The ornamental design for a jewelry display case, substantially as shown.
